AEROSOL DISPENSER CAP

Robert H. Abplanalp, Bronx, N. Y.

Application December 16, 1955, Serial No. 39,360

Term of patent 14 years

(Cl. D62—2)

Fig. 1

Fig. 3

Fig. 1 is a perspective view showing the top and one side of an aerosol dispenser cap embodying my new design.

Fig. 2 is a perspective view showing the top and the opposite side of the cap.

Fig. 3 is a central vertical section through the cap.

I claim:

The ornamental design for an aerosol dispenser cap, as shown.
